C. J. ROHLAND

ALTERNATING CURRENT ELECTRIC BELL

Original Filed April 12, 1916

UNITED STATES PATENT OFFICE.

CURT J. ROHLAND, OF SEEKONK, MASSACHUSETTS, ASSIGNOR, BY MESNE ASSIGNMENTS, TO SIGNAL ENGINEERING AND MANUFACTURING COMPANY, OF NEW YORK, N. Y., A CORPORATION OF MASSACHUSETTS.

ALTERNATING-CURRENT ELECTRIC BELL.

Application filed April 12, 1916, Serial No. 90,757. Renewed October 9, 1922. Serial No. 593,459.

To all whom it may concern:

Be it known that I, CURT J. ROHLAND, a citizen of the German Empire, residing at Seekonk, in the county of Bristol and State 5 of Massachusetts, have invented a new and useful Alternating-Current Electric Bell, of which the following is a specification.

This invention relates to a sound producing device preferably in the form of a bell or gong, but also containing features 10 suitable for application to a horn or the like, and it relates to a device of this kind intended to be operated solely by an alternating magnet.

15 The principal objects of this invention are to provide a device of this character in which the armature of the electro-magnet and the plunger, which is adapted to engage the gong or diaphragm for producing 20 sound, move together and in which the means for moving the armature back from the coils after it is attracted to them shall be of an extremely simple and durable character; and especially to provide means 25 whereby the armature and plunger can be tuned, so to speak, so as to cause them to vibrate naturally in harmony with the alternations of the current so as to produce a maximum of efficiency. The invention also 30 involves other features of construction and details as will appear hereinafter.

Reference is to be had to the accompanying drawings, in which

Fig. 1 is a front elevation of an electric bell and its operating mechanism constructed in accordance with this invention;

Fig. 2 is a sectional view on the line 2—2 of Fig. 1, and

Fig. 3 is a plan of the operating mechanism showing the casing in section.

The invention is shown in a form in which it involves a frame or casing 10 provided with a tongue 11 thereon for supporting the gong 12. This gong is mounted in an 45 eccentric bushing as is usual so that it can be turned for adjusting purposes.

Mounted within the casing are a pair of magnet spools or coils 15. These may be connected up with electric wires or cables 50 16 for operation by an alternating current. Located near the top of the casing is a bracket 17 having a flat shelf transverse to the axes of the coils and provided with two integral guiding projections 18 in a ver-

tical plane. This is provided with a projecting tongue 19 in the plane of the shelf. Preferably this tongue and also the whole bracket is made of sheet brass or other material that is nonmagnetic. Thus it constitutes a spring for receiving the impact 60 of the armature.

This tongue is provided with a perforation and the casing is provided with a perforation in alignment with it. These two perforations receive and guide an operating 65 plunger 20 so that it moves in a direction parallel with the axes of the two coils and half-way between them. Fixedly mounted with respect to the plunger is a soft iron armature 21. This is located under the 70 tongue. Surrounding this plunger for a very large portion of its length is a coiled spring 22. This is of comparatively heavy 75 design and of considerable strength. The spring bears against a nut 23 which is screwed 80 threaded on the plunger so that it can be adjusted back and forth, and a projection 24 extending down from the armature engages the knurled or toothed edge of this nut and acts as a lock to hold it in adjusted 85 positions.

In the use of the device the gong is turned and adjusted to the proper position to be engaged by the plunger when attached to cause it to sound with a maximum loudness. 85 It is fastened in position in the usual way. The electro-magnet at each alternation, attracts the armature in opposition to the spring. When the current changes and passes through its period of minimum 90 strength the spring overcomes the attraction of the magnet and forces the armature back toward the tongue 19. The armature, as will be observed, is guided by the downwardly depending guides 18 while the 95 plunger is guided by the perforations in which it is mounted.

The purpose of the adjustment is to get the compression of the spring exactly to the right point so that the whole structure consisting of the spring, plunger and armature will vibrate in harmony with the alternations of the electric current. This is an important and delicate matter, for after having once secured this result the turning of 100 the nut slightly in either direction will very 105 materially alter the loudness with which the gong is operated. With this construction

the nut itself serves to transmit the action of the spring to the plunger. The spring bears on the nut and in itself resists the turning thereof on the plunger. However 5 the nut can be turned by hand and it is not likely to be turned accidentally because of the pressure of the spring upon it and the lock 24 located behind it.

I am aware of the fact that in direct current operating devices for bells and the like 10 springs have been used for forcing the plunger in one direction for the purpose of making or breaking a contact, but in that case the spring was not used as in this case 15 for tuning purposes, and could not be. It will be observed that with this construction the simplest possible arrangement of spring is secured and no bending or twisting of it is necessary for the purpose of securing 20 the right adjustment. The adjustment is mechanical and exact and also permanent. When in normal position with no current flowing the spring supports the armature but is not under other compression, but it resists the motion of the armature 25 toward the electro-magnets until the current is near its maximum. Also on the return stroke the spring resists the action of the magnet on the armature until the current 30 is near its minimum and then lifts it. This construction will operate also even when the device is turned to any other position.

Although I have illustrated and described 35 only a single form of the invention and shown it as applied only to a bell or gong, I am well aware of the fact that modifications can be made therein and that the invention can be applied to other similar sound producing devices without departing from the scope of the invention as expressed in the claims. Therefore I do not wish to be limited 40 to all the details of construction herein shown and described, or to the particular 45 application of the device illustrated, but what I do claim is:—

1. In a sound producing device, the combination with an alternating current electromagnet, its armature, and a device to be vibrated, of a reciprocating plunger fixedly connected with the armature and movable therewith, a coiled spring located on said plunger for forcing the armature away from the coils, said plunger having a screw thread, 50 a nut fitting said screw thread and engaged by the end of the spring, said nut constituting means by which the spring actuates the plunger, and a locking device carried by the armature and engaging the nut to hold it in 55 its adjusted positions.

2. In a sound producing device, the combination of a pair of electro-magnet coils, a guide plate located adjacent thereto and provided with guiding means in a plane par-

allel with the plane of the axes of said coils 65 and having a tongue of spring metal projecting therefrom, said tongue having a perforation, a casing for containing said elements, said casing having a perforation in alignment with the first named perforation, 70 a plunger mounted to slide in said perforations, an armature fixed to said plunger and movable therewith, and a spring for moving said plunger and forcing the armature against said spring tongue when the current 75 in the coils is in a weak condition.

3. In a sound producing device, the combination of an alternating current electromagnet coil, a guide plate located adjacent thereto, and provided with guiding means in 80 a plane parallel with the axis of said coil and having a tongue of spring metal projecting therefrom, a plunger mounted to slide in a direction parallel to the axis of the coil, an armature fixed to said plunger 85 and movable therewith, and a coil spring encircling the plunger for forcing said armature against said spring tongue when the current in the coils is in a weak condition, the armature being forced against the action of 90 said spring and away from said spring tongue to effect a sound producing stroke when the current in the coils is in a strong condition.

4. In a sound producing device, the combination of an alternating current electromagnet, its armature, and a device to be vibrated, of a reciprocating plunger fixedly connected with the armature and movable therewith, a coil spring for forcing the armature away from the magnet and a guide plate having a guide portion for engagement with the side of the armature, and a spring tongue in the path of movement of the armature away from said magnet.

5. In a sound producing device, the combination with a device to be vibrated, of an alternating current electromagnet, an armature therefor, a reciprocating plunger movable with the armature to strike said device during the movement of the armature toward the magnet, a coil spring for forcing the armature away from the coils of the magnet, a non-magnetic shock-absorbing spring stop in position for limiting the movement of the armature away from the magnet during a weakened condition of the current strength between alternations, and means for varying the tension of said coil spring to tune the device and secure return 110 movement of the armature and plunger against said spring stop during time intervals corresponding with the current reversals.

In testimony whereof I have hereunto set 125 my hand.

CURT J. ROHLAND.
